UNITED STATES PATENT OFFICE.

JOHN CORGIAT, OF GILLESPIE, ILLINOIS, ASSIGNOR OF ONE-FOURTH TO FELIX RONCHETTI, OF BENLD, ILLINOIS.

RAIL.

1,099,428.

Specification of Letters Patent.

Patented June 9, 1914.

Application filed September 6, 1913. Serial No. 788,469.

To all whom it may concern:

Be it known that I, JOHN CORGIAT, a subject of the German Emperor, residing at Gillespie, in the county of Macoupin and State of Illinois, have invented certain new and useful Improvements in Rails, of which the following is a specification, reference being had to the accompanying drawings.

This invention relates to rail connections.

One of the objects of the invention is to provide an improved form of rail connection which is applicable to railway rails, stair rails, or any other form of rail or beam which is liable to expand considerably under varying temperatures.

Another object of the invention is to provide a rail connection of this character which is simple of construction and application, comparatively inexpensive, and thoroughly practical and efficient.

In the accompanying drawings which supplement this specification, Figure 1 is a side elevation view of a rail joint; Fig. 2 is an end elevation of a rail illustrating the cross-shaped tongue; and Fig. 3 is an end view of the adjacent rail end illustrating the cross-shaped recess.

In these drawings in which similar reference characters correspond with similar parts throughout the several views, I have illustrated my invention as applied to the meeting ends of two railway rails, the end of one rail being generally designated by the numeral 5, the end of the other rail 35 being designated 6. The medial portions of these rails are the same as that of an ordinary railway rail; the end portions, however, being substantially rectangular in cross section. The end 5 of each rail is provided 40 with a horizontal slot 7 which extends medially between the top and bottom entirely across the rail end, a vertical slot 8 extending from the bottom to the top of the rail and intersecting the slot 7 medially and 45 at right angles. The opposite end of the rail, or the contiguous end of the adjacent rail is provided with a horizontal rib 9 which extends medially between the top and bottom entirely across the rail, a vertical

rib 10 intersecting the rib 9 at right angles 50 and extending from the top to the bottom of the rail. It will be seen that these two ribs 9 and 10 combine to form a cross, and the arms are of such dimensions as to snugly fit into the intersecting slots 7 and 8, which 55 combine to form a cross-shaped recess. It is also to be observed that the outer faces of the ribs 9 and 10 are flat and flush one with the other, while the side walls of each of such ribs 9 and 10 are disposed in parallelism.

It is obvious that when the rails are fitted together, that the cross-shaped boss or tongue extends into the cross-shaped recess, the rail ends are positively secured against 65 relative lateral movement, either vertically or horizontally; but they are free to move longitudinally relative to one another, so as to compensate for expansion and contraction.

From the foregoing it is obvious that I have provided a rail connection which is fully capable of attaining the desired objects, as specified in the foregoing, in a thoroughly practical and efficient manner.

While the accompanying drawings illustrate what I believe to be the preferred embodiment of my invention, it is to be understood that the invention is not limited thereto, but that various changes may be made 80 in the construction, arrangement and proportions of the parts without departing from the scope of the invention, as defined in the appended claim.

What I claim is:—

In a rail joint, the combination of a rail having the web at an end portion increased in thickness substantially the width of the head of such rail, the end face of the rail thus afforded being provided with a vertically disposed tongue at substantially the transverse center thereof extended along the entire height of the rail, the end face of such tongue being flat and the side walls thereof being disposed in parallelism, and a horizontally disposed tongue intersecting the vertical tongue and disposed at substantially the center of height of the rail, the

end face of such tongue being flat and disposed flush with the end face of the vertical tongue, the side walls of such horizontal tongue being also disposed in parallelism; 5 with a second rail, an end portion of which has its web similarly thickened as the end portion of the first rail and being provided in its end face thus afforded with grooves

adapted to snugly accommodate the ribs on the end face of the first named rail. 10

In testimony whereof I hereunto affix my signature in the presence of two witnesses.

JOHN CORGIAT
